UNITED STATES PATENT OFFICE.

EDWIN NORTON, OF LAKE PLACID, NEW YORK.

ART OF MANUFACTURING SHEET-METAL CANS.

933,104.

Specification of Letters Patent.

Patented Sept. 7, 1909.

Application filed May 29, 1908. Serial No. 435,648.

To all whom it may concern:

Be it known that I, EDWIN NORTON, a citizen of the United States, residing at Lake Placid, in the county of Essex and State of New York, have invented certain new and useful Improvements in the Art of Manufacturing Sheet-Metal Cans, of which the following is a specification.

This invention relates to the art of manufacturing sheet-metal cans, and has particular reference to the simultaneous manufacture of a plurality of cans from a single body, such as that shown and described in a companion application for patent. In my said companion application I have shown and described an improved article of manufacture, to-wit, a cylindric can, and a new method of making the same. The article as sold by the manufacturer to the packer comprises a cylindric body closed at both ends and having circumferential flange formations intermediate the closed ends. These cans while in the state of storage at the place of manufacture, or during shipment to the packer, are designed to be kept completely closed and in an air-tight condition so as to exclude from the interior all foreign or objectionable matter. When the packer desires to utilize the cans the cylindric body will be severed or cut at the intermediate flange formation so that the single can with both ends closed, will produce two cans each having an end closed by a head, and an end open with an outward-turned flange at the open end, to which flange another head may be readily attached after the can has been filled.

The inventive idea here involved may find expression in various mechanical forms, and I have shown one of such forms in the accompanying drawings; but it is to be distinctly understood that said drawings are intended for the purpose of illustration only and not as defining the limits or scope of the invention.

In the drawings,—Figure 1, is a perspective view of a sheet-metal cylinder long enough for two can-bodies of the standard size, and illustrates the first step in the method of manufacture of the cans. Fig. 2 is a longitudinal section of the cylinder, and shows the second step in the method of manufacture of the cans. Fig. 3, is a side view of the bicylinder can,—the two ends having the heads attached which completely closes the cylinder. Fig. 4, is a sectional

view of a can-head. Fig. 5, is also a side view of the closed bicylinder can and shows the third step of the method,—to-wit, the closing or bumping of the intermediate circumferential flange. Fig. 6, also shows a side view of the closed bicylinder can mounted so as to be revolved and shows the final step in the method. Fig. 7, shows a vertical sectional view through the can body,—the section being taken on the line 7—7 of Fig. 5. Fig. 8, is a similar view of the can body while held and undergoing the final operation,—this section being taken on the line 8—8 of Fig. 6, and Fig. 9, shows in perspective the two cans produced by the final operation of severing the cylindric body.

In order to manufacture cans that are to be of a certain size when complete and ready for filling, a blank must first be cut from the sheet of metal of a length equal to the combined length of the bodies to be simultaneously produced from the single body. The blank of the required length having been produced is then rolled or folded into a cylinder, A, and the longitudinal or side seam is secured. This seam may be of any desired construction either lap or lock, but in the present instance the cylinder is provided with a lap seam, b, which may be made tight by fusing or soldering in any suitable manner.

The formation of a cylinder long enough for a plurality of bodies, and the closing of the side seam constitutes the first step in the method. The next two steps in the method may be readily alternated for the reason that the cylinder is to be provided with lateral outward end-flanges and also with exteriorly-projecting circumferential flange formations between the two end flanges, and it is immaterial to the final result which of these is produced by the second step, or whether they be produced simultaneously. For the purposes of the present case however, it is deemed sufficient to state that the cylinder formed by the first step is then subjected to such well-known operations as will produce the lateral and outwardly-projecting end-flange, e, as clearly shown in Fig. 2. The preparatory flange formation, c, located intermediate the two ends may then be produced by clamping the cylindric body, A, in a separable or two-part ring, 1, having an interior circumferential groove, 2; and by using a suitable rotary beading tool, 3, on a crank-arm, 4, and bringing the cylindric body

and said tool together, so the latter will have position on the interior of the cylinder as seen in Fig. 2, and then by revolving the cylinder, A, an interior V-shaped groove is formed 5 circumferentially around the wall of the cylindric body, which produces on the exterior of the said body an expansion or an outwardly-projecting flange or bead, c. For the primary formation of this circumferential, intermediate flange, the V-shape shown at, c, in Fig. 2, is deemed preferable because of constructive reasons,—tools that will produce this shape may be readily applied to the cylinder and operated. After the preparatory flange formation has been produced in the cylindrical body the opposite ends thereof should be closed by applying heads or ends, g, thereto. These heads are attached to the ends of the body preferably 10 by a double-seam joint,—the flange of the head and the flange, e, on the body being folded or rolled together in the usual manner. When the ends of the body have been closed the body will have the form of a long 15 can, as illustrated in Fig. 3, and the intermediate preparatory flange, c, will have the form shown in the same figure and the completely-closed can-bodies in this condition 20 may be sold as articles of commerce. In some instances however, it may be deemed 25 advantageous to compress the two walls of the V-shaped bead, c, and bring said V-walls close together, so as to form the double-wall 30 circumferential flange, d. This serves to increase the stiffness of the walls of the body 35 at the center, and at the same time completes the preparatory formation of the said intermediate flange. The particular form of devices for effecting this closing operation of 40 the V-walls is immaterial, but for the purpose of illustration, one form of device is shown in Fig. 5 in which the cylindric body, A, with both ends closed is placed in a separable holder comprising the two center rings, 45 6, the end plates, 7, and rods, 8, connecting the end-plates and rings. Cams, 9, or other devices adjacent the said end-plates serve to force said plates and rings toward each other, and by this lateral pressure either at 50 the ends of the body or at opposite sides of the intermediate flange, c, cause said flange-walls to close together as seen in Fig. 5.

It will thus be understood that the empty 55 b cylindric cans, closed at both ends, and having the intermediate flange in the form shown at either, c, or, d, may be stored indefinitely without liability of crushing or damage to the walls such as occurs to the empty open-top cans; and moreover as there 60 are no openings or cracks of any kind in the can-body, dirt and dust cannot settle therein and the interior of the cans will remain clean and ready for use upon separating the cylindric body into two parts at said intermediate 65 flanges.

To effect a separation or a severance of the can-body at the intermediate flange I mount the body between two heads, 10, which may be rotated in any suitable manner, and while thus revolving the body the metal or rim- 70 edge that connects the two walls of the intermediate flange, d, is cut and thus the body is severed and separated into two parts. The grinder or cutter, 11, for splitting the intermediate flange or bead, d, may 75 be mounted on a shaft, 12, which may be revolved in a direction reverse to that in which the can-body, A, turns. By reference to Fig. 9 it will be seen that upon severing the body at said previously-formed flanges, d, the two 80 complete can-bodies of the desired size will be simultaneously produced. Each body being complete and having an open end with a complete flange, 13, around the latter and the opposite end closed by the head, g. 85

Having thus described my invention what I claim and desire to secure by Letters Patent is,—

1. The method of manufacturing a plurality of can-bodies, consisting in first forming a single body of a length equal to the combined length of all the bodies to be produced from the single body, then producing one or more exteriorly-projecting preparatory flange formations around the body in- 95 termediate the two ends thereof, and finally splitting the said preparatory flange formations.

2. The method of manufacturing a plurality of can-bodies, consisting in first forming a single body of a length equal to the combined length of all the bodies to be produced from the single body; then producing one or more preparatory flange formations around the body intermediate the ends there- 100 of; subjecting the body to longitudinal pressure to compact the said flange formations, and finally severing the body by splitting said flange formation or formations.

3. The method of manufacturing a plurality of can-bodies consisting in first forming a cylindric body of a length equal to the combined length of two bodies to be produced from the single body; producing a preparatory flange formation around the 115 body intermediate the ends thereof; applying heads to the two ends of the single body; applying endwise pressure to the body to compact the said flange formation, and finally severing the body into two parts by splitting said flange formation.

4. The method or improvement in the art of manufacturing sheet-metal cans, consisting in first forming a cylindric body; producing in the wall of said body an outward-projecting circumferential bead midway between the ends of the cylindric body; attaching heads to the two opposite ends of said body and finally circumferentially splitting the said outward bead. 125 130

5. The method or improvement in the art of manufacturing sheet-metal cans, consisting in first forming a cylindric body; grooving the body circumferentially from the inside thereof to produce an exterior double-wall flange intermediate its ends; permanently closing the two opposite ends of the grooved body; pressing the closed ends of the body toward the said intermediate circumferential groove and causing the double

walls thereof to contact, and finally severing the cylindric body at the double wall flange so as to form two cans each having a flanged open end.

In testimony whereof I affix my signature 15 in presence of two witnesses.

EDWIN NORTON.
